UNITED STATES PATENT OFFICE.

CHARLES A. WOOLSEY, OF MINNEAPOLIS, MINNESOTA.

CRATE.

Application filed January 29, 1925. Serial No. 5,501.

My invention relates to crates or receptacles adapted to contain articles such as milk or cream bottles for shipping and transportation purposes, and the object of the invention particularly is to provide improved means for securing the bottom of the crate to the walls thereof to the end that the bottom will be supported in a strong substantial manner, but can be easily and quickly removed for repair or other purposes.

A further object is to provide a bottom-supporting means of convenient application to the crate and of strong durable construction and capable of withstanding the rough hard usage to which a shipping package of this kind is usually subjected.

A further object is to provide means for reinforcing and alining the slats of the walls, and bottom to aid in holding them together in proper relation when the walls are assembled.

Other objects of the invention will appear from the following detailed description.

The invention consists generally in various constructions and combinations all as hereinafter described and particularly pointed out in the claims.

In the accompanying drawings forming part of this specification,

Figure 1 is a perspective view of a crate embodying my invention;

Figure 2 is a similar view of the bottom removed from the crate;

Figure 3 is a transverse sectional view through the crate showing the manner of mounting the bottom therein and the strengthening means which I prefer to employ for the walls;

Figure 4 is a detail sectional view taken on a section line at right angles substantially to the section line of Figure 3;

Figure 5 is a perspective view of the crate bottom showing a slightly modified construction; and

Figure 6 is a sectional view taken at one end of the plate transversely of the bottom supporting means.

In the drawing, the side walls of the crate are represented by comparatively narrow slats or bars 2, 3 and 4 arranged in parallel relation, one above the other and spaced apart and the end walls are designated by similar slats 5, 6 and 7, also spaced apart and secured to the abutting ends of the side walls by the metallic reinforcing corner

plates 8 and 9 fitting the outer and inner faces of the walls at the corners. The slats 2 and 5 at the top of the crate are preferably thicker than the middle slats to reinforce and strengthen the walls and provide bumpers to take up the shock or strain on the crate resulting from its contact with some hard immovable object.

In crates of the depth shown, I prefer to provide these thicker slats only at the top of the walls but in deeper crates, I may provide similar slats at the bottom. I also prefer to provide vertical bores or sockets in the slats of the side walls to receive reinforcing wires 10 which do not preferably extend through the upper and lower slats but terminate at a suitable point therein and not only reinforce the walls of the completed crate but serve as a means for holding the slats of the wall in their parallel spaced relation during the assembling of the walls and the securing of them together at the corners. The intermediate slats of the end walls are preferably cut away as at 11 to allow the convenient insertion of the hand in lifting or moving the crate from place to place. The bottom of the crate is preferably composed of comparatively narrow side slats 12 and similar intermediate slats 13 spaced apart in parallel relation, and the slats 12 are preferably deeper or thicker as indicated at 14 in Figure 2 so that the lower portion of these slats will depend beyond the plane of the bottom of the crate and the walls and form supports or runners for convenience in moving the crates from place to place and also for contact with the nose of a truck which may be used for lifting and moving the crates about. The slats 12 and 13 are preferably transversely bored and a reinforcing means such as wires 15 are inserted therein and have their ends bent backwardly and seated in the side slats as indicated at 16 in Figure 2. These transverse wires not only brace the bottom slats of the crate and hold them in parallel relation, but form a convenient means for keeping the slats in their proper position while the end plates or supports are being secured thereto.

At each end of the slats forming the bottom of the crate, I provide bars or rails 17, preferably of sheet metal of suitable gage, bent to a substantially U-shaped form in cross-section, with upper and lower flanges between which the ends of the slats are in

serted and seated against the rear wall of the rail and firmly secured by suitable means such as rivets 18. These rails are of sufficient length to fit easily between the side walls of the crate near the end walls thereof and in the upper side or flange of each rail I prefer to form a longitudinal bead 19, and into the recesses formed by these beads I insert rods 20 having their ends fitting within sockets in the corner plates of the crate and headed or upset at the extreme ends to firmly secure the rods in the crate and bind the bottom and walls together. The bead or bulge 19 is preferably formed 15 in the upper portion of the rails to raise the rods 20 as far as practicable above the lower edges of the walls so that there will be more metal of the corner plates beneath these rods to support the bottom when the crate is 20 loaded. With this construction, I am able to extend the ends of the bottom slats to a point close to the lower slats of the end walls as will be apparent from inspection of Figures 1, 2 and 4. Although this construction 25 forms an extremely substantial and solid means for mounting the bottom of the crate in the walls thereof I am able to very easily remove the bottom by cutting through the supporting rods as they form the sole supporting means for the bottom slats, and I am 30 thus able at any time to detach the bottom from the crate and repair or replace one or more of the slats of which it is composed. I prefer to make the bottom of a series of 35 parallel slats but it will be understood that this construction may be modified by the use of wider slats or by one continuous plate if preferred. The slat construction, however, is preferable as usually waste pieces of material may be employed and it is less expensive to repair when broken.

In Figures 5 and 6, I have shown a slightly modified construction which consists in providing end rails 21 folded to a 45 U-shaped form with the bent or folded portion forming a loop 22 in the plane of the crate bottom instead of above it as illustrated in the previous figures. Similar rods are provided fitting within the loop at the 50 ends of the slats but the slats in this instance do not extend to a point as near the end walls as in the other constructions and it is necessary to drop the supporting rods a little lower in the corner plates than where 55 the recess or bead is formed in the upper flange of the end rails. For this reason, I may prefer to use the form of rail shown in Figures 1 and 2. The supporting rods will be inserted through holes in the corner 60 plates in the construction shown in Figures 5 and 6 and headed or otherwise secured therein in substantially the same manner as described with reference to the previous figures.

65 I claim as my invention:

1. A container comprising side and end walls, rails having seats for the ends of the bottom of the container, and means extending across said container and mounted in the side walls thereof outside the end walls 70 and supporting said rails.

2. A container comprising side and end walls, rails having seats for the ends of the container bottom, and means extending lengthwise of said rails and engaging them 75 and mounted in the container side walls outside the plane of said end walls.

3. A container comprising side and end walls, rails having loops formed therein and provided with seats for the ends of the container bottom, and means passing through 80 said loops and supporting said rails on the container walls.

4. A container comprising side and end walls, sheet metal rails folded to form seats 85 for the ends of the container bottom, and having loops or folds formed therein, and means fitting within said loops and mounted in the container walls for supporting said rails and bottom.

5. A container comprising side and end walls, rails having seats for the ends of the container bottom, and rods passing lengthwise through said rails and having 90 their ends mounted in said walls, the removal of said rods permitting the removal of the container bottom.

6. A container comprising side and end walls, and reinforcing plates at the corners, rails having longitudinal loops or folds 100 formed in the upper side thereof and also having seats for the ends of the container bottom and rods fitting said loops and having their ends passing through holes in the opposite walls and corner plates and headed 105 thereon.

7. A container comprising side and end walls, rails having seats for the ends of the container bottom, rods extending lengthwise of said rails and engaging the upper portion 110 thereof above the ends of said bottom and permitting said ends to extend to a point close to the end walls of the container, and said rods having their ends extending through the side walls of the container adjacent the corners thereof and secured 115 therein.

8. A fastening means for a container bottom comprising rails of flexible material folded to form opposing flanges between 120 which the ends of the container bottom are inserted and secured, said rails having loops or folds formed by bending the flange thereof, and rods fitting within said loops and having ends adapted to be mounted on the 125 container walls.

9. A container comprising side and end walls, a bottom fitting within said container, rails composed of metallic plates folded lengthwise along a central line to form upper 130

and lower flanges between which the ends of said bottom are inserted, means passing through said flanges and said bottom and securing them together, said rails having longitudinal openings formed in the folding of the rails and rods fitting within said openings and having projecting ends mounted in the side walls of the container, the severing of said rods allowing the separation of 10 said bottom from the container.

10. A container comprising side and end walls, a bottom composed of slats arranged edge to edge, the outer slats being thicker than the intermediate ones, and having bev-

eled ends and terminals of substantially the 15 same thickness as the corresponding terminals of the other slats, the thicker portions of said slats forming runners for raising the container out of contact with the surface over which it may be moved, rails 20 adapted to receive the ends of the slats and means securing them therein, and means for mounting said rails in the walls of the container.

In witness whereof, I have hereunto set 25 my hand this 23rd day of January, 1925.

CHARLES A. WOOLSEY.
